UNITED STATES PATENT OFFICE.

SAMUEL W. AVIS, OF HARTFORD, CONNECTICUT, ASSIGNOR TO THE MERROW MACHINE COMPANY, OF HARTFORD, CONNECTICUT, A CORPORATION OF CONNECTICUT.

GUIDE FOR SEWING-MACHINES.

1,245,306.

Specification of Letters Patent.

Patented Nov. 6, 1917.

Application filed February 19, 1915. Serial No. 9,410.

To all whom it may concern:

Be it known that I, SAMUEL W. AVIS, a citizen of the United States, residing in the city of Hartford, county of Hartford, 5 State of Connecticut, have invented certain new and useful Improvements in Guides for Sewing-Machines; and I do declare the following to be a full, clear, and exact description of the same, reference being had 10 to the accompanying drawings, forming a part of this specification, and to the figures and letters of reference thereon.

This invention relates to guides for use on sewing machines designed to form overseam 15 or covering stitches. In the great variety of work wherein stitches of this character are employed it is frequently desirable to introduce into the finish, a strip of material, as a tape, cord, or ribbon, either to add 20 strength to a seam or edge, to enhance the beauty of the finish, or for other purposes. In some cases alternate inclusion and exclusion of such a strip is effective. Furthermore a desirable result may obtain by presenting a piece of work in one relation to the line of stitch formation when the strip 25 is included therewith, and in another relation to the line of stitch formation when said strip is excluded therefrom.

30 The primary object of my invention is the provision in a machine of the type mentioned of a strip guide, together with mechanism for shifting it from one position to another with respect to the stitch forming 35 mechanism, whereby said guide in one of its positions will direct a strip for inclusion in the finish, while in its other position, said strip will be excluded from the finish.

Another object of my invention is the 40 provision of a fabric guide associated with the mechanism for shifting the strip guide, whereby movement of the elements thus associated will be interdependent.

Other objects of the invention will here- 45 inafter appear.

In the drawings, I have shown in detail one convenient form of embodiment of my invention which is fully set forth in the following description. I do not, however, 50 limit myself to the exact construction illustrated as I may depart therefrom in many

respects within the scope of the invention as defined by the claims following said description.

Referring to the drawings:—

Figure 1 is a front view partly in section of a shell stitch crochet machine showing my invention included therewith.

Fig. 2 is a plan view of a part of the machine shown in Fig. 1 illustrating one 60 position of the guides.

Fig. 3 is a view similar to Fig. 2 illustrating another position of the guides.

Fig. 4 is a sectional detail view of guide shifting mechanism.

Fig. 5 is a detail view of a part of the mechanism shown in Fig. 4.

Fig. 6 is a view in isometric projection of the guides and mechanism co-operative therewith, and,—

Fig. 7 is a detail view of feed mechanism.

Throughout the several views of the drawings similar characters designate similar parts.

One of the many styles of stitching in 75 connection with which my invention may be used advantageously is that employed in producing a finish for the raw edges of knit underwear. In effecting such a finish upon apparel it is sometimes requisite that a tape 80 be included with the finish along certain portions of the edge, as for example, about the neck of a garment, where it may serve as reinforcement or as an adjusting draw string.

85 One particular style of edge finish well adapted for the alternate inclusion and exclusion of a tape, as in the procedure briefly suggested, is the shell stitch, such as may be produced on a crochet machine of the well known Merrow type.

In the United States Patent #414,234 issued Nov. 5, 1889, stitches of this character are described and the method of producing them is set forth, also in United 95 States Patent #1,045,163 issued Nov. 26, 1912, there is described a machine for producing the crochet shell stitch finish.

Such machines are well known in the art to which my invention appertains, and inasmuch as the one illustrated in the drawings is of this type, it may, with respect to

its general construction, be briefly described as follows:—

The eye pointed needle designated by numeral 1, is carried by a needle bar 2, mounted for reciprocation in bosses 3, and 5 4, projecting from the head 5, of the machine frame 6.

Reciprocation of needle bar 2, is effected through needle bar clamp 7, link 8, needle 10 bar lever 9, and pitman 10, the latter engaging eccentric 11, on driving shaft 12, which is provided with the usual driving pulley as 13.

In addition to the needle 1, the stitch 15 forming mechanism includes a crochet hook 14 and a supplemental thread carrier 15, both of which are operated by mechanism which does not fully appear in the drawings of the present case but which has been fully 20 shown and described in United States Patents already mentioned and to which reference may be had.

The numeral 16 designates the presser foot, 17 the work plate, 18 the needle plate, 25 19 the chaining finger, 20 the feed dog and 21 the frame cap. A piece of fabric, in which are shown several of the crochet shell stitches, is designated by 22. In forming such stitches as are shown the feed dog 21 is 30 actuated to feed the work only at intervals of several stitch forming cycles. During non-feeding intervals the crochet hook 14, in its oscillating reciprocating movement co-operates with the needle 1, to form a series 35 of loops emanating from a single point of needle penetration in the work, said loops extending around the edge of the fabric, including the chaining finger 19, and also a tape as 23, when the latter is included in the 40 edge finish. Besides forming the loops just mentioned the crochet hook also enchains therewith and with each other, loops of needle and supplemental thread to produce an outer edge border.

45 Introduction into the edge finish of tape 23, as inferred, is best effected at the point near where loops of thread are formed over the chaining finger 19. For the purpose of directing said tape to this point the tape 50 guide 25 is employed. Said guide is shiftable from a point where tape 23 carried thereby will be included in the edge finish (see Fig. 3) to a point where it will be excluded therefrom, (see Fig. 2) and vice 55 versa. Mechanism for so shifting this tape guide in a convenient manner will now be described.

Supported by the frame cap 21 is a stud 26 held rigidly in place by a pin 27. The 60 enlarged head 28 of said stud has a bore 29 to receive therein one end of a plunger as 30 terminating at its outer end in a push button 31 backed by a spring 32 and having near its other end a socket arm 33 to receive the 65 shank 34 of tape guide 25. Sleeved upon

the head 28 is a cylinder 35 having at its inner end an integral flange 36 engaging the reduced shank of stud 26. At its outer end said cylinder is provided with a flanged cap 37, having a hub 38 which is bored to fit and 70 guide plunger 30. Screws 40 secure cap 37 to cylinder 35 and these members when so assembled, while free to oscillate upon head 28 are longitudinally confined with respect thereto, thus forming a longitudinally fixed 75 element, angularly movable with the tape guide by virtue of an arrangement that will now be explained.

Extending through from the bore 29 to the outer surface of the enlarged head 28 of 80 stud 26 is a spirally disposed slot 41 and contiguous to this slot, cylinder 35, and the flange of cap 37, are provided with a straight longitudinally extending slot 42. Through both of these slots 41 and 42 is extended 85 socket arm 33, whereby when plunger 30 is moved longitudinally, a swinging or arcuate movement will be imparted to said arm 33 and cylinder 35, due respectively to the inclination of slot 41 and the engagement of 90 arm 33 with slot 42 all for a purpose that will hereinafter more clearly appear.

The spring 32 before mentioned is confined between the push button 31 and cap 37 and exerts a constant tendency to force 95 plunger 30 outward from the position in which it is shown in Figs. 1, 2, 4, and 6. Referring to these figures it will readily be seen that such outward movement of plunger 30 together with socket arm 33 would effect 100 also a swinging movement thereof about the longitudinal axis of the plunger due to the guiding effect of spiral slot 41. Thus a compound movement comprising a movement bodily and angularly would be imparted to said arm 33 and to the tape guide 25 whereby the delivery end of the latter moving in a helical path would pass from a point above and slightly to the rear of the 105 stitch forming elements to a point just in advance thereof and practically in the plane of the chaining finger 19, which finger is preferably grooved as at 43 to receive the tape guide head. This is the position said 110 guide occupies when delivering tape to be included in the edge finish. To shift the guide so that the tape will be excluded from the edge finish, push button 31 may be pressed to effect the reverse of the operation just described, thus restoring the tape guide 115 to the position where its delivery end is above and to the rear of the stitch forming elements.

For convenience, the position occupied by the tape guide when tape is to be excluded 120 from the edge finish, will hereinafter be referred to as its upper position while the other position it assumes will be referred to as its lower position.

When the tape guide 25 is in its lower po- 130

sition the spring 32, through the parts described, tends to keep it in definite relation to the chaining finger 19, and incidentally, in proper relation to the stitch forming elements. It follows that said guide 25 must in accordance with the construction shown, be swung to its upper position against the tension of spring 32. To retain it in this upper position and in order that, when so desired, it may be readily released to automatically assume its lower position, a trip latch as 44 is employed. As shown, said latch comprises a ring surrounding the cylinder 35, and held against longitudinal movement thereon by and between, an outwardly extending flange 45 at the inner end of said cylinder, and the flange 46, of cap 37. A spring 47 surrounds a slightly reduced portion of said latch ring 44, the ends of said spring being attached respectively to the ring and to flange 45 of cylinder 35, from which it follows that a suitable tension on the spring will tend to rotate the ring. Beyond a certain extent however, this rotation is limited by a stop pin 49 in flange 45 which acts against a shoulder 50 formed by a finger piece 51 attached to ring 44. The latch portion of ring 44 is formed by a slot 52, one side of which is notched as at 53, and provided with an inclined edge 54 leading thereto from the open end of said slot. When ring 44 is in its normal position or in other words when it has been shifted by spring 47 in the direction indicated by arrow "A," until shoulder 50 engages stop pin 49, the inclined edge 54 will extend across the slot 42, and intersect the path of socket arm 33. Therefore when the tape guide 25 is shifted to its upper position in the manner already described, the socket arm 33 moving inwardly engages the inclined edge 54 of slot 52 in ring 44 and positively rotates the latter away from its stop 49, against the tension of spring 47, until said guide 25 approaches its upper position and socket arm 33 reaches notch 53, whereupon the locking ring is forced into locking relation.

When the socket arm 33 is thus engaged by the latch ring 44, the tape guide will of course be held in its upper position and the tape extending diagonally from the tape guide will pass clear of the stitch forming elements to and under a guide spur 55 projecting from the presser foot 16. While it is not wholly essential to employ this guide spur 55 it is very useful to maintain a definite relation between the work and the tape in either position of the tape guide.

To effect the shifting of tape guide 25 from its upper to its lower position it is simply necessary to trip the latch 44 by a slight upward pressure on the finger piece 51, thus releasing the parts which will be actuated by spring 32.

When finishing the edge of material without including the tape it is frequently desirable to have the line of needle penetration extend deeper into, or farther away from the edge of the fabric than when tape 70 is included within the edge finish, and to that end the fabric edge guide 60 is connected with the tape shifting devices to automatically change the position of the fabric guide when the position of the tape 75 guide is changed. While this guide might be set independently of the tape guide shifting mechanism, much time can be saved and accuracy assured by associating it there-with in the manner now to be explained. 80

Pivoted at one end to a boss 56 on the inner flange of cylinder 35, is a link 61 provided at its other end with a pivotal connection to a slide 62, said pivotal connection comprising the stud 63. The function of 85 slide 62 will hereinafter appear. Slotted at 64 to engage stud 63 is a lever 65 pivoted on a stud 66 supported by the frame cap 21. Pivotedly connected to lever 65 by the stud 67, which is adjustable in slot 68, is a link 90 69 also pivotally connected by the stud 70 with a slide 71 which is mounted on frame cap 21. At the forward end of slide 71 is adjustably secured by screw 72, the fabric edge guide 60. Through the connections 95 described it will be apparent that when the tape guide 25 is shifted to its lower position, the fabric edge guide 60 will be shifted in a direction to decrease the depth of stitch, while when the tape guide is shifted to its 100 upper position, the fabric edge guide will be shifted in the opposite direction to increase the depth of stitch. In other words, shifting tape guide 25 to its lower position and to its upper position will respectively 105 cause the fabric edge guide 60 to be moved to the left and to the right as viewed from the front of the machine. Should a reversal of this shifting action imparted to the fabric edge guide be desired, it may be effected by attaching link 61 to the boss 57 instead of the boss 56 (see dotted lines, Fig. 5) in which case the overhanging lip 59 of the edge guide would be removed or an edge guide without the said overhanging lip 115 would be substituted for the one shown. The extent of movement imparted to the edge guide may be varied by adjusting the stud 67 in the slot 68, also the relative location of the field of movement of said edge guide 120 may be changed by adjusting it upon the slide 71 by means of the screw 72.

From the foregoing it will be clear that shifting of both the tape guide 25 and the fabric edge guide 60 are effected by force 125 applied to plunger 30 in the direction of its longitudinal axis, said force being applied either directly by the machine operator or by the spring 32. Furthermore, longitudinal movement of slide 62 is obviously ef- 130

fected in a similar manner due to its connection through link 61 with cylinder 35. This movement of slide 62 is transferred through the yoke 73 to a lever 74 the latter 5 being associated with feed controlling mechanism designated in a general way by the numeral 75. This mechanism in itself constitutes no part of my present invention. It is fully shown and set forth in a pending 10 application, filed in the United States Patent Office November 2, 1914, Serial Number 869,936 and therefore need not be herein described in detail.

It is the function of this feed controlling 15 mechanism to vary the duration of the hereinbefore mentioned non-feeding intervals, *i. e.* one setting of the mechanism may effect a non-feeding interval of sufficient duration to include eight stitch forming 20 cycles of the stitch forming elements whereby a shell composed of eight stitches will be produced, while another setting may shorten the non-feeding interval to include only four stitch forming cycles, so that a 25 shell of only four stitches will be produced. The arrangement shown to effect a coöperation between the guide shifting devices and the feed controlling mechanism permits of an edge finish being produced in which the 30 shells formed when the tape is included therein will be made up of a different number of stitches than when said tape is excluded therefrom. It will be understood, however, that the feed employed may be 35 uniform in its character, in which event the tape and edge guide shifting mechanism would be entirely independent of the feed controlling mechanism. Also the tape guide shifting mechanism while well adapted for 40 association with the fabric edge guide, may be independent thereof. The invention is not limited in this respect but resides more particularly in the relation of the tape guide and its peculiar shifting mechanism 45 to the stitch forming elements.

Having thus described my invention, what I claim is:—

1. In a sewing machine, the combination 50 with stitch forming elements, a support, a bodily and angularly movable tape guide carried by said support and shiftable into operative and inoperative relation with respect to the stitch forming elements, a movable latch for holding said tape guide in a 55 position to which it may be shifted manually and mechanism for bodily and angularly shifting the tape guide to another position when the latch is released.

2. In a sewing machine, in combination 60 with stitch forming elements, a support having a bore and an inclined slot, a plunger shiftable in the bore of the support, and provided with an arm extending through the inclined slot in said support, whereby 65 bodily movement of said carrier in the di-

rection of its longitudinal axis will also cause a swinging movement thereof about the same axis, and a tape guide secured to the arm.

3. In a sewing machine, in combination 70 with stitch forming elements, a support, a tape guide carried by the support, mechanism for simultaneously moving the tape guide bodily and angularly to change its position with respect to the stitch forming 75 elements, and a fabric edge guide positively operable in opposite directions by the tape guide.

4. In a sewing machine, in combination 80 with stitch forming elements, a support, a tape guide carried by the support, mechanism for simultaneously moving the tape guide bodily and angularly, to change its position with respect to the stitch forming 85 elements, a fabric edge guide operatively associated with the mechanism for moving the tape guide, and mechanism for varying the amplitude of movement of one of said guides for a given movement of the other 90 guide.

5. In a sewing machine, in combination 95 with stitch forming elements, a support, a tape guide carried by the support, mechanism for simultaneously moving the tape guide bodily and angularly to change its position with respect to the stitch forming elements, a fabric edge guide operatively associated with the mechanism for moving the tape guide, mechanism for varying the amplitude of movement of one of said 100 guides for a given movement of the other guide, and means for changing the relative position of the guides.

6. In a sewing machine, in combination 105 with stitch forming elements, a stationary support having a slot, a pair of movable members carried by the support, one of said movable members having a slot angularly disposed with respect to the slot in the support, and a tape guide carried by the 110 other member and engaging both of said slots whereby movement of one of the members will cause the tape guide to move in a helical path into or out of operative relation with respect to the stitch forming elements.

7. In a sewing machine, in combination 115 with stitch forming elements, a support, a bodily and angularly movable tape guide carried by said support and shiftable into operative and inoperative relation with respect to the stitch forming elements, a hollow cylinder also carried by said support and angularly movable with the tape guide, a spring actuated latch associated with the 120 cylinder for holding the tape guide in one of its positions, spring means for shifting said tape guide to its other position, a fabric edge guide, and means for connecting said fabric edge guide to the cylinder whereby 125 130

the position of the fabric edge guide will be dependent upon the position of the tape guide.

8. In a sewing machine, in combination with stitch forming elements, a support having a bored head provided with an inclined slot, a cylinder loosely surrounding the head of the support and provided with a straight slot, a plunger extending into the bore of the support and manually shiftable in one direction of the extent of its longitudinal axis, a spring for shifting said plunger in the opposite direction, a tape guide secured to the plunger and extending through both the spiral slot in the head of the support and the straight slot in the cylinder, whereby endwise bodily movement of the plunger will cause a like movement and an angular movement of the tape guide and an angular movement of the cylinder, a fabric edge guide, and means for transferring motion from the cylinder to said fabric edge guide.

9. In a sewing machine, in combination with stitch forming elements, a frame cap, a support secured to the frame cap, a bodily and angularly movable tape guide carried by said support, a cylinder also carried by said support and movable by the tape guide, a slide mounted on the frame cap, a fabric edge guide secured to said slide, and means interposed between the cylinder and the slide whereby movement of said cylinder will shift said slide.

35 10. In a sewing machine, in combination with the stitch forming elements, a chaining finger having a groove, a tape guide, and mechanism for shifting the tape guide in a helical path to change its position with respect to the groove of the chaining finger.

11. In a sewing machine, in combination with stitch forming elements, a frame cap, a support secured to the frame cap, a bodily and angularly movable tape guide carried by said support, a cylinder also carried by said support, and movable by the tape guide, a pair of slides mounted on the frame cap, a fabric edge guide secured to one of said slides, feed mechanism controlled by the other slide and operable to change the character of finish produced by the stitch forming elements, and means for connecting the cylinder with both of the slides whereby movement of said cylinder will effect movement of said slides.

55 12. In a sewing machine, in combination with stitch forming elements, a support, a tape guide carried by the support, means for simultaneously moving the tape guide bodily and angularly, to vary its relation to the stitch forming elements, a pair of slides, a

fabric edge guide secured to one of the slides, feed mechanism controlled by the other slide and operable to change the character of finish produced by the stitch forming elements, and means for associating both of the slides with the tape guide whereby movement of the latter will effect movement of the slides.

65 13. In a sewing machine, in combination with stitch forming elements, a support, a bodily and angularly movable tape guide carried by the support, a longitudinally fixed element angularly movable with the tape guide, a latch associated with said element 75 for holding the tape guide in one position, and mechanism for moving the tape guide to another position.

14. In a sewing machine, in combination with stitch forming elements, a support, a 80 bodily and angularly movable tape guide carried by the support, a longitudinally, fixed element angularly movable with the tape guide, a latch associated with said element 85 for holding the tape guide in one position, mechanism for moving the tape guide to another position, and an edge guide operatively associated with the longitudinally fixed angularly movable element.

90 15. In a sewing machine, in combination with stitch forming mechanism, a support having a bored head provided with an inclined slot, a plunger longitudinally movable in the bore of the support, a tape guide secured to the plunger and extending through 95 the inclined slot, a spring for moving the plunger to one position, and a latch for holding the plunger in another position.

16. In a sewing machine, in combination with the stitch forming elements, a support 100 having a bored head provided with an inclined slot, a plunger longitudinally movable in the bore in the support and having a projection in engagement with the inclined slot, a tape guide secured to the plunger, a spring 105 for moving the plunger to one position, and a latch for holding the plunger in another position.

17. In a sewing machine, in combination with stitch forming elements, a movable tape 110 guide, an element adjacent to the tape guide and operable thereby, a pair of slides, a fabric edge guide secured to one of the slides, feed mechanism controlled by the other slide, and means for connecting the tape guide 115 actuated element with both of the slides, whereby movement of the tape guide will effect correlated movement of the slides.
